UNITED STATES PATENT OFFICE.

HENRY A. WEIHMAN, OF PHILADELPHIA, PENNSYLVANIA, ASSIGNOR TO
JOHN F. SIMONS, FREDERICK M. SIMONS, AND EDWIN S. SIMONS, OF
SAME PLACE.

DESIGN FOR A THIMBLE.

SPECIFICATION forming part of Design No. 22,547, dated June 20, 1893.

Application filed April 10, 1893. Serial No. 488,827. Term of patent 7 years.

To all whom it may concern:

Be it known that I, HENRY A. WEIHMAN, of the city and county of Philadelphia and State of Pennsylvania, have invented and produced a new and original Design for Thimbles, of which the following is a specification, reference being had to the accompanying drawings, in which the design is shown.

Figure 1 is a side elevation of a thimble having my design applied; and Fig. 2 is a diagrammatic view of the same.

A is the upper crown portion of the thimble. B is the band about the thimble below the crown to which the design is applied.

The following are the leading features of the design:

C is a representation of the Capitol at Washington, and D is a representation of the President's Mansion or "White House." These parts C and D are upon the band B. Each of

these parts C and D are inclosed by an ornamental border c, d. Located between the parts C and D is a representation of the Washington Monument E.

A portion of the surface of the band B is left plain or unornamented as at F. This plain or unornamented portion is inclosed by an ornamental border f.

Having now described my design, I claim as my invention and desire to secure by Letters Patent—

The design for a thimble substantially as described and shown in the accompanying drawings.

In testimony of which invention I have hereunto set my hand.

HENRY A. WEIHMAN.
